C. E. WILCOX

LOCK FOR WELL CASING ELEVATORS

Filed Jan. 29, 1921

Inventor:
Charles E. Wilcox

By *James T. Parker*,
his attorney

UNITED STATES PATENT OFFICE.

CHARLES E. WILCOX, OF ANAHEIM, CALIFORNIA, ASSIGNOR TO E. C. WILSON, OF LOS ANGELES, CALIFORNIA.

LOCK FOR WELL-CASING ELEVATORS.

Application filed January 29, 1921. Serial No. 440,932.

To all whom it may concern:

Be it known that I, CHARLES E. WILCOX, a citizen of the United States, residing in Anaheim, county of Orange, State of California, have invented new and useful Improvements in Locks for Well-Casing Elevators, of which the following is a specification.

This invention has to do with pipe or casing elevators such as are used in connection with oil and water wells etc., and it is an object of the invention to provide a simple, effective and reliable device of this character.

It is a particular object of this invention to provide means, in connection with a casing engaging structure embodying a plurality of relatively moving parts, to securely and positively lock the parts around the casing so that there is no liability of them being released when in operation.

A noteworthy feature of the invention is the provision of a simple and effective construction and arrangement by which the objects of the invention are carried out. The structure is such as to be durable, simple, and reliable in operation.

The various objects and features of the invention will be best and more clearly understood from the following detailed description of a preferred embodiment of the invention throughout which reference is had to the accompanying drawings in which—

Fig. 1 is a plan section of a typical casing elevator embodying the present invention, being a sectional view taken immediately above the casing engaging structure of the elevator, as indicated by line 1—1 on Fig. 2; Fig. 2 is a side elevation of the device shown in Fig. 1 being a view taken as indicated by line 2—2 on Fig. 2; Fig. 3 is a detailed sectional view taken as indicated by line 3—3 on Fig. 2 showing the latch device, and the positive locking device; and Fig. 4 is a sectional view similar to Fig. 1 showing the latch device set and the positive locking device actuated or set to positively lock the latch device.

Throughout the drawings numeral 10 designates the casing engaging structure to which supporting links 11 connect. In the particular elevator which I illustrate to facilitate a clear disclosure of my invention the casing engaging structure 10 is formed

with notches 12 which carry the links 11. The notches 12 are of such size and configuration and the links 11 are so shaped and proportioned that the points of contact between the links and the structure 10 are as close as possible to the center of load carried by the elevator, and are such that the links 11 can be placed in and removed from the notches 12 when in certain positions and properly manipulated. The details of the notches and links, etc., are more fully set forth and are claimed in my co-pending application entitled Well casing elevators, filed on even date herewith and bearing the Serial No. 440,933.

The type of structure 10 in connection with which the present invention is adapted to be employed comprises a plurality of relatively movable parts. In the particular case herein set forth the structure 10 comprises two parts A and B connected together at one end by a vertical hinge pin 13, and having their other ends adapted to swing to open and close the elevator. As means for connecting the free ends of the parts A and B when the structure is arranged around a casing a T-shaped latch 15 is mounted on the part A to cooperate with suitable lugs 16 on the part B. The latch 15 comprises a shank 17 with a transversely extending head 18 at its outer end. At its inner end the latch shank 17 is mounted on a vertical pivot shaft 27. Shaft 27 is mounted in lugs 19 on part A and has a coiled spring 20 arranged in connection with it. One end of the spring 20 is connected to the part A and the other end to the shaft 27. The spring 20 tends at all times to rotate the shaft 27 in the direction indicated by the arrow in Fig. 1. The lugs 16 on part B are spaced and arranged so that when the parts A and B are together, as around a casing, the shank 17 of the latch 15 passes between the two lugs allowing the head 18 to pass behind or outside of the lugs. The head 18 of the latch 15 is adapted to engage the front surface of the lugs 16 as the parts A and B are moved together, thus causing the latch 15 to be swung outwardly against the resistance of spring 20 until the parts A and B are together and the head is in position to drop behind the lugs 16. When the head 18 of the latch 15 is behind the lugs 16 the parts A and B are held together, the latch 15 being held in locked position by the spring 20. The structure thus

far set forth is more clearly and fully set forth, and is the subject of Patent Number 1,314,996 issued September 2, 1919 to Elihu C. Wilson and a pending application of 5 Elihu C. Wilson filed April 20, 1920, Serial No. 375,332, entitled Well elevators. I have herein set forth this particular type of latch device merely to illustrate the general character of means for connecting the elevator 10 parts, in connection with which the present invention may be embodied. It is therefore to be understood that the present invention is not in any way limited or restricted to this particular form of connecting means 15 or in fact to any specific form of connecting means.

In combining a typical form of the present invention with the particular latch device hereinabove set forth the part B is provided with a recess 30 at a point between the lugs 16. The latch 15 is provided at its inner side with a lug 31 adapted to extend into the recess 30 when the parts A and B are latched together, as illustrated throughout 20 the drawings. There is a vertical opening 35 in the part B above the recess 30 and opening downwardly into the recess 30. The upper portion 36 of the opening 35 is round and somewhat smaller than the bottom portion 37, which is square. There is a vertical square opening 38 in the projection 31 positioned in the projection to register with the opening 35 when the lug 31 is in place in the recess 30. The opening 35 opens upwardly 25 into a notch 40 in the part B, and a rod 41, round in cross section at its upper end and square in cross section at its lower end, is arranged in the opening 35 so that its upper end portion extends through the upper portion 36 of the opening 35 and upwardly through the notch 40 while its lower end portion is slidably carried in the lower portion 37 of the opening 35. At the upper end of the rod 41 is mounted a head 43 at 30 the two ends of which are downwardly extending lugs 44. The head 43 extends over a portion of the part A and also a portion of the part B and recesses 45 are formed in the parts A and B to receive the head 43 so that it can be arranged in engagement 35 with the two parts A and B and have its upper surface 47 flush with the upper surfaces 48 of the parts A and B. Suitable notches 49 are provided in the recesses 45 to receive the projections 44. A compression spring 50 is arranged in the notch 40 between the part B and the head 43 to tend at all times to press the head upwardly and thereby cause the rod 41 to assume the position shown in Figs. 2 and 3 of the drawings. The rod 41 is limited in its upward movement by its squared portion reaching the upper end portion of the opening 35 through which it cannot pass. It will be obvious, of course, how various means other than the

particular one herein set forth may be provided for limiting the upward movement of the rod 41. When the rod 41 is in the up position as shown in Figs. 2 and 3, its squared portion is wholly within the squared portion of opening 35, and does not project into the recess 30 or into the opening 38 in lug 31. However, when the rod 41 is in its lower position, or is down, as shown in Fig. 4, and when the head 43 is seated in 70 the recesses 45 with the projections 44 in the notches 49, a portion of the squared part of the shaft 49 extends into and through the opening 38 in lugs 31, thus positively retaining the lug 31 in the recess 30. A portion of the opening 35 being squared and a portion of the rod 41 being correspondingly squared to slidably fit within the squared portion of the opening 35 holds the rod 41 so that it cannot rotate and thereby allow 75 the head 43 to get into a position where it will not seat in the recesses 45 when the rod is moved downwardly.

In the operation of the device the parts A and B are placed around a casing 60, the latch device automatically operating to connect them in this position in the manner hereinabove described. The structure 10 is then lifted or moved upwardly by the links 11, causing the upper surface 47 of the head 43 to engage the lower edge 61 of the casing collar 62. As the structure 10 continues to move upwardly the head 43 seats in the recesses 45 with the projection 44 in the notches 49, and the squared portion of the rod 41 extends downwardly into the opening 38 in projection 31 in the manner hereinabove described. When the head 43 is completely seated in the recesses 45 and the lug 31 is positively retained in the recess 30, the upper faces 48 of the parts A and B are in engagement with the lower edge 61 of the casing collar so that further upward movement of the structure 10 will cause lifting of the casing. The lugs 44 in extending into the notches 49 positively hold or retain the upper portion of the free ends of parts A and B together, while the squared portion of the rod 41 positively locks the projection 38 in the recess 30 and therefore the latch 15 in place behind the lugs 16. When the structure 10 is lowered away from the collar 62 the spring 50 forces the head 43 and rod 41 upwardly until they reach the position shown in Figs. 2 and 3, whereupon the latch 15 can be easily released or swung outwardly to allow the structure 10 to be opened and removed from the casing. It may be said that the operation of the positive locking means is automatic. As the structure 10 is put into operation, by being moved to engagement with the collar 62, the positive locking means automatically positively locks the parts A and B and the latch mechanism, simultaneously, so that the structure 10 is 100 105 110 115 120 125 130

securely and positively held against release-
ment. When the structure 10 is relieved of
its load and is in position to be released
from the casing the positive locking means
5 has become released so that it does not in
any way interfere with the releasement of
the latch. In practice it is preferred that the
spring 50 be comparatively heavy or strong
so that it will be sure to lift the head and
10 rod from the down position. Although I
prefer to provide means for directly hold-
ing the parts A and B together when the
latch device is positively locked, it will be
obvious how the latch device might be posi-
15 tively locked without the means for directly
holding the parts A and B, and how the
means for directly holding the parts A and
B might be provided without the positive
locking of the latch device. In practice it
20 is of particular advantage that the positive
locking device should be automatic as it
eliminates all possibility of a workman for-
getting or failing to set the positive locking
device and thereby leave the elevator in
25 condition where it might possibly release
while in operation.

Having described a preferred form of my
invention, I claim:

1. In a device of the character described
30 embodying two relatively movable members
adapted to embrace a casing, the combina-
tion of a latch to releasably connect the
members in position embracing the casing,
and a separate means to independently con-
35 nect the members in said position and lock
the latch.
2. In a device of the character described
embodying two relatively movable members
adapted to embrace a casing the combina-
40 tion of, a latch to releasably connect the
members in position embracing the casing,
and a separate means to independently con-
nect the members at a point removed from
the latch.
- 45 3. In a device of the character described
embodying two relatively movable members
adapted to embrace a casing the combina-
tion of, a latch to releasably connect the
members on the casing, and a separate
50 means actuated by the casing collar to con-
nect the members and lock the latch when
in its latching position.
- 55 4. A device of the character described,
comprising two clamping and holding mem-
bers hinged together and adapted to em-
brace between them a casing, said members
each having a recess, a latch adapted to re-
leasably connect said members in position
embracing the casing, a rod carried by one
60 of the members adapted to be actuated to
lock the latch in its latching position and
a part in connection with the rod adapted
to seat in the recess and directly connect
the members when the rod is in its latch
65 locking position.

5. A device of the character described,
comprising two clamping and holding mem-
bers hinged together and adapted to em-
brace between them a casing, said members
each having a notched recess, a latch adapt-
70 ed to releasably connect said members in
position embracing the casing, a rod car-
ried by one of the members adapted to be
actuated to lock the latch in its latching po-
sition, a member in connection with the rod
75 to yieldingly hold it out of its latch locking
position, a member on the rod, and projec-
tions on said member, the member and projec-
tions being adapted to seat in the notched
recesses when the rod is in its latch locking
80 position to directly connect the members.

6. A device of the character described,
comprising two clamping and holding mem-
bers hinged together and adapted to em-
brace between them a casing, each of said
members having an upwardly facing notched
85 recess and one of said members having
an opening, a latch adapted to releasably
connect said members in position embracing
the casing, the latch having an opening
adapted to register with the first mentioned
90 opening when the latch is in its latching
position, a rod carried in said first men-
tioned opening adapted to be actuated to
extend into the opening in the latch when
the two openings are in register, a head on
95 the rod adapted to fit within the recess
when the rod is in actuated position, projec-
tions on the head to extend into the
notches of the recesses when the rod is in
100 actuated position, means for holding the
various parts in position so that the head
and projections will properly cooperate
with the notched recesses when the rod is
actuated, and means to normally yieldingly
105 hold the rod in its unactuated position in
which position the head is above said mem-
bers.

7. In combination with a casing having
a collar, an elevator for the casing com-
prising two clamping and holding mem-
bers hinged together and adapted to em-
brace between them the casing, each of
110 said members having an upwardly facing
notched recess and one of said members
having an opening, a latch adapted to re-
leasably connect said members in position
embracing the casing, the latch having an
115 opening adapted to register with the first
mentioned opening when the latch is in its
latching position, a rod carried in said first
mentioned opening adapted to be actuated to
extend into the opening in the latch when
120 the two openings are in register, a head on
the rod adapted to fit within the recess
when the rod is in actuated position, down-
wardly extending projections on the head
to extend into the notches of the recesses
125 when the rod is in actuated position, means
for holding the various parts in position
130

so that the head and projections will properly cooperate with the notched recesses when the rod is actuated, and means to normally yieldingly hold the rod in its unactuated position in which position the head is above said members, said rod being adapted to be actuated by engagement of the head with the collar of the casing when said members are moved into engagement with the collar.

8. In combination with a casing having a collar, an elevator for the casing comprising two clamping and holding members hinged together and adapted to embrace 15 between them the casing, one of said members having an opening, a latch to releasably connect the members in position embracing the casing, the latch having an opening to register with the first mentioned 20 opening when the latch is in its latching position, a rod carried in the first mentioned opening adapted to be actuated to extend into the opening in the latch, and a spring in connection with the rod to normally 25 yieldingly hold the rod in an unactuated position where its outer end extends beyond said members, the rod being adapted to be actuated by the outer end of the rod engaging the collar of the casing upon the 30 members being moved into engagement with the casing.

9. A device of the character described, comprising two relatively movable casing

embracing members, a latch to hold the members in casing embracing position, a locking member separate from the latch and engageable with the latch to lock it in latching position, and a head on the locking member adapted to be engaged by the casing and to engage said members to hold them in casing embracing position.

10. A device of the character described comprising two relatively movable casing embracing members, a latch to connect and hold the members in casing embracing position, and another connecting member separate from the latch and adapted to be actuated by reason of engagement with the casing collar to connect the casing embracing members independently of their connection by the latch.

11. A device of the character described comprising two relatively movable casing embracing members, a latch to connect and hold the members in casing embracing position, and another connecting member separate from the latch and adapted to connect the casing embracing members independently of their connection by the latch.

In witness that I claim the foregoing I have hereunto subscribed my name this 18th day of January 1921.

CHARLES E. WILCOX.
Witness:
VIRGINIA BERINGER.
